PORTABLE STEAM BOILER

Chester W. Bros, Minneapolis, Minn., assignor to Wm. Bros Boiler & Manufacturing Company, Minneapolis, Minn., a corporation of Minnesota

Application August 26, 1929. Serial No. 388,491

3 Claims. (Cl. 110—4)

This invention relates to new and useful improvements in steam boilers of the portable type.

An object of the invention is to provide a portable boiler comprising two units, one consisting of a suitable steam generator and a supporting structure therefor; the latter including a steel casing provided with a suitable insulating lining, all of which parts are completely assembled to provide the boiler unit; and the second unit constituting the furnace which embodies a structural steel supporting frame, the necessary fire brick and tile to provide the lining for the combustion chamber of the furnace, and a steel casing enclosing the fire brick and tile. All of the parts of each unit are so constructed and assembled as to make each unit self-supporting and self-sustaining, whereby the two units may be safely transported about from place to place without disassembling.

20 A further object is to provide a portable steam boiler comprising a boiler unit and a furnace unit, so constructed that each unit may be completely assembled at the factory for shipment to the point of installation; the furnace unit being so constructed that it may be set up on the job without the usual masonry foundation, commonly required to support a boiler, after which the boiler unit is placed on top of the furnace unit and the joint between the two units over the combustion 25 chamber in the furnace, being sealed by suitable brick work or masonry to the setting up of the boiler, as a whole.

The particular object of the invention therefore, is to provide a portable steam boiler particularly adapted for use in such places as the oil fields, where it is usually necessary to frequently move about from place to place, as from one well to another, said boiler comprising two completely assembled units which may be readily set up and 30 taken down and transported from place to place without having to destroy the usual brick work and masonry embodied in the construction of the furnace, my improved boiler necessitating only a small amount of masonry or brick work to complete the setting up of the boiler, which masonry is of a temporary nature so that it may be quickly removed to permit removal of the boiler unit from the furnace unit to facilitate handling of 35 the boiler, when transporting the same from one location to another.

Other objects of the invention will appear from the following description and accompanying drawings and will be pointed out in the annexed 40 claims.

In the accompanying drawings, there has been disclosed a structure designed to carry out the various objects of the invention, but it is to be understood that the invention is not confined to 45 the exact features shown as various changes may

be made within the scope of the claims which follow.

In the drawings:

Figure 1 is a vertical sectional view showing the boiler and furnace units assembled to provide the completed boiler;

Figure 2 is a vertical sectional view on the line 2—2 of Figure 1;

Figure 3 is a side elevation of the boiler unit removed from the furnace unit;

Figure 4 is a vertical sectional view on the line 4—4 of Figure 2, showing only the furnace unit;

Figure 5 is a perspective view illustrating a portion of the supporting frame of the furnace unit; and

Figure 6 is a sectional plan view on the line 6—6 of Figure 3.

The portable boiler disclosed in this invention comprises two completely assembled units, one of which will hereafter be referred to as the boiler unit and the other as the furnace unit.

The boiler unit includes a structural steel frame comprising base members 1 and 2, preferably of I-beam cross section as shown in Figures 1 and 2, and upper beams 3 supported upon the base members 2 by suitable upright members 4 and 5, preferably H-shaped in cross section, as shown in Figure 6. The upright members 4 and 5 extend above the beams 3 as best shown in Figure 3.

The form of steam generator here shown is of the three drum type, comprising an upper drum 6, an intermediate drum 7, and a lower drum 8, all operatively connected together by banks of water circulating tubes 9, 11, and 12, as shown in Figure 1. The upper drum 6 is supported upon the upper beams 3 of the structural frame by suitable brackets 13, and the intermediate drum 7 is suspended from these beams by suitable brackets 14, shown in Figure 3. The lower drum 8 is suspended from the tube banks 11 and 12 in the usual manner to allow for expansion and contraction. The upper drum 6, commonly known as the steam drum, is shown provided with the usual steam nozzle 16, while the lower drum 8 is provided with the usual blow off or drain 17. Suitable baffles are provided in connection with the tube banks to direct the products of combustion thru the generator in the manner indicated by the arrows in Figure 1.

The steam generator is enclosed within a suitable casing formed from a plurality of metal plates suitably secured together and supported by the frame members 2 and 3. The casing is lined with a suitable insulating material 21 to prevent conduction of heat through the casing walls. The upper wall of the casing is shown as being reinforced by a plurality of cross members 22 to prevent distortion of the upper wall thereof. The casing is provided with the usual smoke outlet 23 upon which the stack, not shown, is adapted 120

to be connected. A damper 24 is shown in the smoke outlet 23 to control the flow of gaseous fumes therethru.

The furnace unit, upon which the boiler unit is 5 adapted to be demountably supported, also includes a structural supporting frame here shown as comprising side frame members 25 connected together by cross members 26, 27, and 28, shown in Figures 1 and 2. The frame members 25, 26, 10 27, and 28 are preferably of channel cross section and are comparatively wide so as to provide a substantial support for the furnace when the boiler is completely assembled. Because of the 15 relatively large ground engaging areas of the base members 25 to 28, inclusive, the furnace, with the boiler unit supported thereon, may be set up on the ground surface without the use of a foundation constructed of masonry, such as is commonly used in boiler set ups.

20 Suitable uprights 29, 31, and 32 are secured to the side base members 25 and have their upper portions suitably connected together by means of channel members 33 and 34 and cross channels 35, 36, and 37.

25 The side walls 38 of the furnace and also the front and rear walls 39 and 41, respectively, are here shown constructed of suitable fire tiles 42 supported upon brackets or hangers 40, secured to the upright frame members 29, 31, and 32 as 30 shown in Figures 1, 2, and 4. Suitable fire bricks 43 are shown interposed between the tiles 42 to complete the formation of the walls. Openings 44 are provided in the front wall 39 of the furnace adapted to receive suitable oil or gas burners for the introduction of fuel into the furnace.

35 The rear wall 41 of the furnace extends above the side walls 38 and front wall 39 as shown in Figure 4, and is reinforced by means of a transverse plate 45 secured to a cross member 46, by 40 suitable brackets 47, as shown in Figure 5. The cross member 46 is preferably secured to the upright frame members 31. A hanger 40 is secured to the upper portion of a transverse plate 45 to provide a support for the upper row of tiles 45 42 as shown in Figure 4. By constructing the boiler and furnace unit, as above described, two units may be completely assembled at the factory and shipped as complete units to the place where the boiler is to be used, thereby greatly reducing 50 the cost of setting up the boiler on the job, because of the elimination of the operation of constructing and assembling each individual unit on the job.

55 From the foregoing, it will be seen that the portable boiler herein disclosed, comprises two units, each adapted to be completely assembled at the factory and shipped in such condition to the location where it is to be used. The two units are so constructed that the boiler may 60 readily be placed upon the furnace, after which the joint between the two units over the combustion chamber is sealed by suitable masonry, indicated by the numerals 48 in Figures 1 and 2. When the boiler unit is placed upon the furnace 65 unit, the base frame members 1 and 2 of the boiler unit will engage the upper ends of the uprights 29, 31, and 32, as shown in Figures 1 and 2. The structural supporting frames of the two units are so constructed that the two units need 70 not be bolted or otherwise secured together when the two units are set up as shown in Figures 1 and 2, the only means necessary to secure together the two units consisting of the masonry or brick work 48, shown in Figures 1 and 2.

75 It will thus be seen that very little masonry is

needed to set up the boiler on the job. When the boiler has completed its period of use in a certain location, the two units may be quickly disassembled by simply destroying the sealing masonry or brick work indicated by the numerals 48, after which the boiler unit may be removed from the furnace unit, and the two units placed on suitable skids or other transporting means, for transportation from one place to another. The cost of setting up and taking down the boiler has been reduced to a minimum because the construction of masonry and brick work on the job has substantially been dispensed with, and, because of its novel construction, the boiler may be set up and taken down in a comparatively short time without having to destroy the walls of the furnace, as is now common practice when using furnaces of ordinary construction. The furnace walls are preferably provided with suitable air circulation passages 49, 51, and 52, as shown in Figures 1, 2, and 4.

80 In the drawings, I have shown a three drum type of steam generator, but it is to be understood that the invention is not limited to this particular type of generator as other types suitable for the purpose may be used without departing from the scope of the invention.

85 I claim as my invention:

1. A portable fire box unit for water tube boilers comprising relatively wide ground engaging 105 members forming a rigid and substantially rectangular base, uprights connected to and rising from said base, a substantially rectangular frame connected to said uprights and spaced from said base, and fire brick supported upon the framework between said base and frame and forming the walls of said furnace, said framework and brick walls forming a unitary structure which can be moved about from place to place as a unit without disassembling.

110 2. A portable fire box unit for water tube boilers comprising relatively wide ground engaging members forming a rigid and substantially rectangular base, uprights connected to and rising from said base, a substantially rectangular frame connected to said uprights adjacent the upper ends thereof, the upper ends of said uprights forming a support for a detachable boiler unit, fire brick and tile supported upon the framework between said base and frame and forming the walls of said furnace, and one of said walls having a reinforced portion projecting above the other walls, said framework and walls forming a unitary structure which can be moved about from place to place as a unit without disassembling.

115 3. A portable fire box unit for water tube boilers comprising relatively wide ground engaging members forming a rigid and substantially rectangular base, uprights connected to and rising from said base, a substantially rectangular frame connected to said uprights and spaced from said base, plates secured to the outer faces of said uprights between said base and frame and forming the outer walls of said fire box unit, a plurality of hangers secured to the inner faces of 140 said uprights, and fire brick and tile connected to said hangers and forming inner walls spaced from said outer walls to provide air circulating passages between said walls, said framework and walls forming a unitary structure which may be 145 moved about from place to place as a unit without disassembling.

CHESTER W. BROS.
